United States Patent

Des. 236,833
Patented Sept. 16, 1975

236,833

INTEGRATED CIRCUIT PACKAGE

Robert J. Beall, San Jose, Calif., assignor to
Amdahl Corporation, Sunnyvale, Calif.

Filed July 24, 1972, Ser. No. 274,459

Term of patent 14 years

Int. Cl. D13—99

U.S. Cl. D26—1 R

Fig. 2

Fig. 1

Fig. 3Fig. 4FIG. 1 is a side elevational view of the integrated circuit package showing my new design;

FIG. 2 is a top plan view thereof looking in the direction of the arrows 2—2 of FIG. 1;

FIG. 3 is a bottom plan view thereof looking in the direction of the arrows 3—3 of FIG. 1; and

FIG. 4 is a perspective view thereof looking in the direction of arrow 4 in FIG. 1.

I claim:

The ornamental design for an integrated circuit package, as shown.
